United States Patent Office

Des. 215,494
Patented Sept. 30, 1969

215,494

POSTAGE SCALE

Bernard Eblowitz, 68-07 61st Road,
Middle Village, N.Y. 13379

Filed Aug. 16, 1968, Ser. No. 13,159

Term of patent 14 years

Int. Cl. D10—99

U.S. Cl. D52—10

Fig. 1.

Fig. 2.

Fig. 4.

Fig. 3.

FIGURE 1 is a perspective view of a postage scale, in closed condition, showing my new design;

FIGURE 2 is a side elevational view thereof;

FIGURE 3 is a bottom plan view thereof;

FIGURE 4 is an end elevational view thereof;

FIGURE 5 is a perspective view of the scale as it appears when opened and in use;

FIGURE 6 is a bottom plan view of FIG. 5;

FIGURE 7 is a top plan view thereof; and

FIGURE 8 is an end elevational view thereof.

The undisclosed side of the postage scale in both the closed and opened position is the same in appearance as the sides shown respectively.

I claim:

The ornamental design for a postage scale, substantially as shown and described.
